UNITED STATES PATENT OFFICE.

FRANZ TRINKS, OF BRUNSWICK, GERMANY.

CALCULATING-MACHINE.

1,081,172.

Specification of Letters Patent.

Patented Dec. 9, 1913.

Application filed August 14, 1913. Serial No. 784,777.

To all whom it may concern:

Be it known that I, FRANZ TRINKS, manufacturer, citizen of the Duchy of Brunswick, Empire of Germany, residing at Brunswick, 5 Germany, have invented, certain new and useful Improvements in Calculating-Machines, of which the following is a specification.

My invention relates to improvements in calculating machines, and more particularly in calculating machines in which setting disks are provided for operating the registering mechanism, and in which teeth provided on the said setting disks are adapted 10 to be shifted into operative positions by cam disks, the numbers of the teeth which are thus shifted corresponding to the values to be transmitted to the registering mechanism. Machines of this type are shown for example 15 in the patents of the United States No. 928,083, granted to me July 13, 1909, No. 953,242, granted to me March 29, 1910, and No. 1,040,059, granted to me October 1, 1912. In machines of this class the cam 20 disks are provided with fingers which project through slots of the cover of the machine casing. These fingers should not be made too long, because they take part in the revolution of the crank of the machine. 25 Such short finger pieces are inconvenient in operation, and it has therefore been suggested to provide special setting levers which for the purpose of setting the setting disks are coupled with the cam disks, and 30 which are disconnected from the cam disks while the crank is being operated. In this construction the finger pieces which are located outside the casing may have any desired 35 length and suitable form. Constructions of this kind have been described in the patent of the United States No. 843,506, granted to me February 5, 1907. In constructions of 40 this kind more or less complicated clutch members are necessary, such as are shown 45 for example in the patent of the United States No. 979,358, granted to me December 20, 1910. Constructions of this kind are 50 objectionable, because it is impossible to provide the same in old machines. Besides 55 some of the constructions are objectionable, because special levers are provided at the sides of the cam disks, which results in a considerable increase of the length of the setting mechanism. In other constructions the setting mechanism must be shifted in axial direction while the crank is being ro-

tated, in order that the cam disks and the setting levers which are slidingly mounted on the cover of the casing are disconnected from each other.

The object of the improvements is to provide a mechanism for setting the cam disks which permits the use of auxiliary levers of any desired length and convenient form, which is simple in construction, which can 60 be mounted in any old calculating machine in which the cam disks are provided with the ordinary short finger pieces, and which does not necessitate an increase of the length of the setting mechanism nor axial or other 65 movements of the setting mechanism for coupling purposes.

In my German Patent No. 181,681 of July 18, 1906, a calculating machine is described in which means are provided for rapidly re-setting a number which has been removed from the setting mechanism, which means consist in their essential parts of fixed or adjustable stop members adapted to be moved into the path of the finger pieces of 70 the cam disks which upon rotation of the machine crank move in the slots of the cover of the casing, so that the said stop members are engaged by the finger pieces and lock the 75 cam disks during the further rotation of the crank into the position of rest. Thereby the cam disks are set according to the desired 80 number by their movement relatively to the crank. In the said German patent apart from various examples embodying this principle an example is shown in Fig. 6 in which a plate is hinged to the upper margin of the machine, the form of the plate corresponding to the curved form of the cover of the casing. The plate is equipped with parallel 85 slots which are perpendicular to the pivot of the plate and are open at the front end of the plate. Each of the slots is equipped with a slide which provides the 90 aforesaid stop member for the finger piece of 95 the co-operating cam disk. When the hinged plate is rocked downward its slits are in register with the slits of the cover of the casing. Such auxiliary setting devices can 100 be used for setting the cam disks while the crank is in inoperative position, for which purpose the plate is rocked downward on the cover of the casing and the cam disks are rotated by shifting the slides away from the axis of the hinge.

My invention consists in providing means in ermediate an auxiliary setting mechanism

of this or other constructions and the driving mechanism of the machine, whereby the said auxiliary mechanism is shifted out of setting position while the machine crank is being rotated.

For the purpose of explaining the invention more in detail several examples embodying the same have been shown in the accompanying drawings, in which the same letters of reference have been used in all the views to indicate corresponding parts.

In said drawings—Figure 1, is a front view of a calculating machine equipped with the auxiliary setting mechanism, the said auxiliary setting mechanism being shown rocked upward, and the cover of the casing being partly removed, Fig. 2, is a cross-section of the machine taken on the line 2—2 of Fig. 1, Figs. 3 to 5 are partial front views showing modifications of the auxiliary setting mechanism, and Fig. 6, is a cross-section similar to that shown in Fig. 2 and showing a further modification.

Referring to the example illustrated in Figs. 1 and 2, above the upper rear margin of the casing of the machine a shaft 1 is mounted in bearings 16 providing a rocking support for a covering plate 2 which is curved to correspond to the cover 3 of the casing. In slits 4 of the cover 2 slides 5 are shiftable, supported which are formed on their lower sides with ribs 6 disposed in the direction of the slits. The slides 5 are adapted to be locked in position in the slits by suitable locking means which can readily be loosened. To show what may be done I have shown spring actuated clutch members 7 which frictionally engage the plate 2. When shifting the slides 5 the ribs are brought into position for engagement with the finger pieces 8 of the coöperating cam disks 9 so as to carry the same along when shifting the slide 5 in the direction of the arrow for setting the cam disk.

Prior to rotating the crank the setting plate 2 which carries the slides 5 must be removed out of the path of the finger pieces 8 to permit free rotation of the latter. However thereby the operation of the machine is made more difficult, and if by mistake the plate is not removed, the whole calculation would be made erroneous. For this reason my invention consists in providing means for automatically removing the auxiliary setting mechanism 2 from the finger pieces 8 when the rotation of the machine crank is started, so that the finger pieces are free to take part in the rotation of the crank 10. At the end of the rotation of the crank the setting mechanism 2 is returned into operative position. The auxiliary setting mechanism may be removed either by shifting the same laterally or by rocking the same upward.

In the example shown in Figs. 1 and 2

the auxiliary setting mechanism is removed by shifting the plate 2 laterally which shifting movement is imparted to the plate by the axis 11 of the setting mechanism. For this purpose the said axis is provided with a disk 12 having a cam groove 13 formed therein which is engaged by one end of a rocking lever 14 having its fulcrum at a point intermediate its ends on a pivot 15. The opposite end of the rocking lever bears on the front end of the shaft 1 of the plate 2, which shaft is longitudinally shiftable in its bearings 16. Thereby when rotating the crank 10 the shaft 1 and the plate 2 mounted thereon are shifted to the left during the first part of the rotation, so that the stops or ribs 6 are removed out of the paths of the finger pieces 8. At the end of the rotation of the crank the lever 14 which is positively rocked by the cam disk 12 arrives again in the position shown in Fig. 1, so that a pressure spring 17 can return the shaft 1 with the plate 2 mounted thereon into operative position.

When resetting the machine, which may be done for example by mechanism shown at the lower right part of Fig. 2 and described in detail in the patent of the United States No. 823,875 granted to me April 26, 1906, the slides 5 which are held merely by their frictional engagement with the plate 2 are returned into their zero positions. Thereby all the slides are reset in the most simple way by turning the shaft 20 by means of the thumb nut 19 and causing the arms 21 of the said shaft to engage at the rear of pins 9' of the cam disks and returning the same into zero position, as is known in the art. The cam disks which are thus being reset return by their finger pieces 8 the slides 5 into their zero positions. While the thumb nut 19 is in inoperative position the arms 21 are disposed at such distances away from the pins 9', that the cam disks can be freely rotated by the machine crank 10.

The means for bringing the slides 5 into engagement with the finger pieces 8 of the cam disks may be constructed in a different way.

In Fig. 3, I have shown an example in which the plate which carries the slides for engaging the finger pieces of the cam disks is positively shifted in both directions. As shown in the said figure the rocking lever 14' which is adapted to be operated by the cam disk 12' is formed at its upper end with a slot 14'' which engages a pin 23 secured to the shaft 1' of the plate 2'.

In Fig. 4 I have shown a further example in which the cam disk 22 for shifting the shaft 1'' is formed at its side with a cam face. The lever 14''' and the shaft 1'' are connected with each other in the manner shown in Fig. 3. The spring 24 is a drag spring. The cam face of the disk 22 is in

the form of a tooth 22' which rocks the lever 14''' only in the inoperative position of the crank 10 so as to hold the plate 2''' in operative position.

5 In Fig. 6 I have shown an example in which the plate 2''' is adapted to be rocked upward with its slides away from the finger pieces secured to the cam disks, which may also be done by means of a cam disk. As 10 shown the shaft 1''' of the plate 2''' is connected with a crank arm 25 which is jointed to one end of a rocking lever 26. The opposite end of the said lever bears on a disk 28 secured to the driving shaft 11''. If desired 15 the lever may be provided with an antifriction roller 27. The disk 28 is formed at its circumference with a notch 28' and the end 27 of the lever is adapted to be brought into engagement with the said notch by the 20 weight of the plate 2''', as soon as the crank of the machine arrives in its zero position. This position is shown in Fig. 6. As soon as the rotation of the crank is started the disk 28 rocks the lever 26 so as to swing

the plate 2''' upward. Thereby the stop 25 members 6''' provided on the slides are removed out of the paths of the finger pieces 9' of the cam disks.

I claim herein as my invention:

In a calculating machine, the combination 30 with the setting mechanism comprising cam disks which are equipped with projecting finger pieces, and the operating mechanism for the machine, of a member carrying devices located in position for operating said 35 finger pieces, and an operative connection between said operating mechanism and said member arranged to remove the said member with its devices out of position for engagement with said finger pieces 40

In testimony whereof I have hereunto set my hand in presence of two subscribing witnesses.

FRANZ TRINKS.
